Frank J. Plummer

United States Patent Office.

FRANK J. PLUMMER, OF WORCESTER, MASSACHUSETTS, ASSIGNOR TO
R. BALL & CO.

Letters Patent No. 66,519, dated July 9, 1867.

IMPROVEMENT IN PLANING MACHINES.

The Schedule referred to in these Letters Patent and making part of the same.

KNOW ALL MEN BY THESE PRESENTS:

That I, FRANK J. PLUMMER, of the city and county of Worcester, and Commonwealth of Massachusetts, have invented certain new and useful Improvements in Matcher and Planing Machines; and I do hereby declare that the following is a full, clear, and exact description of the same, reference being had to the accompanying drawings, forming a part of this specification, in which—

Figure 1 represents a front view of so much of a matching and planing machine as is necessary to illustrate my invention.

Figure 2 represents a section on line A B, fig. 1.

Figure 3 represents a section on line C D, fig. 1.

Figure 4 represents a section on line E F, fig. 1, (arrows indicate the line of vision in all the figures,) and

Figure 5 represents a section through the gear and its hub and shaft, by which the distance between the matcher heads is varied.

The nature of my invention consists in so combining the matcher-head or spindle-frame in a planing and matching machine with the bed of the machine, as that the matcher-heads can be turned down out of the way and below the surface of the bed B, to permit of the convenient planing of boards of any desired width. Also in such a peculiar construction of mechanism as that the operation of turning the matcher-heads can be performed in a very-expeditious and convenient manner, and also whereby, when desired, the parts can be adjusted again with equal facility for matching.

To enable those skilled in the art to which my invention belongs to make and use the same, I will proceed to describe it in detail.

In the drawings, A A represent the sides of the frame, and B the stationary part of the bed over which the material is fed. The part C of the bed B to which the matcher-heads or spindle-frames D D' are attached, has heretofore been cast with the bed piece, but is in this instance cast separate from that, and is provided with two arms a, one near each end, which extend back and are hinged to lugs or projections b upon the under side of the bed B. Only one of the arms a and lugs b is shown in the drawings, the others being just opposite those shown. The front part c of the swinging part C of the bed B is made in V form, to fit a V-shaped groove planed in the backs of the upper ends of the matcher or spindle-frames D D'. The matcher-heads E E are placed on the vertical spindles F F, supported at the top by bearings d d fastened to their respective matcher-heads or spindle-frames D D'. The lower ends of the spindles F F are stepped in the bearings e e fast to the frames D D'. Motion is communicated to spindles F by means of pulleys G G secured to the spindles by set-screws f f. From the lower ends of the frames D D' extend the arms H H, having oblong holes g in their enlarged parts I, while from the rear of the enlarged parts I project flanges h, which are grooved or slotted out as seen at i, fig. 4, to receive the ends j of the horns J, which are fitted upon the hubs K of the slotted cam arms L L upon the shaft M, the latter having a groove to receive splines in the hubs K of arms L L, so that while the latter can be moved back and forth upon shaft M, they are caused to revolve or turn with said shaft whenever the latter is turned, by means of power applied to the hand-wheel M' on the end of said shaft, which is supported in proper bearings in the frame A. Just inside of frame A is a ratchet-wheel, N, fast on shaft M, while a pawl, m, is fitted to turn upon a stud, n, which is fastened to the inside of the frame A, as indicated in the drawings. The small ends o o of the bolt-arms O O pass through the oblong holes g g in the enlarged parts I of the arms H H, and are held in place by the nuts p p on their outer ends. The outer ends o' o' of said bolt-arms are also turned down small enough to pass through the slots y in the cam-arms L L, and allow the flanged friction-rolls 1 1 to be shipped on to the ends of said arms, so as to occupy the position as respects the ends of the bolt-arms and cam-arms shown in the drawings for the purpose of lessening the friction between the parts. The friction-rolls 1 1 are held in place by the nuts 2 2. In this instance washers 3 are placed upon the ends o' o' before they are passed through the slots y in the arms L L. These washers, in combination with the flanges 4 4 on the friction-rolls 1 1, serve to retain arms L L and H H in their proper position laterally. The slots y in the arms L from the points 5 to 6 are made upon a circle concentric with shaft M. From the front side of the swinging bed-piece C, and near each end, project two ears 7 7, and between which are hung the bolts 8 8 having nuts 9 9,

so that when the parts are to be used in the positions shown in fig. 1, these bolts 8 8 are turned up between the ears 10 10, which project from the front of the bed B, when nuts 9 9 are turned down upon the top of bed B, thus drawing the swinging bed-piece C up firm against the bottom of piece B. Binder pieces 11 are screwed or bolted to the frames D D', so as to lap upon the shoulder x upon the swinging bed C, thereby retaining them in close contact and yet allowing them to be moved laterally to adjust the distance between the matcher-heads E E.

In practice the frame D' is generally fixed and the other combined with a screw-shaft, P, so that by simply turning said shaft the first matcher-head frame can be adjusted nearer to or farther from the other, as may be desired. The end of screw-shaft P is stepped in the frame D', and passes through frame D, and has a flattened end, 12, which fits in the socket 14 of shaft Q, which passes through the side of frame A, hub or thimble-piece 15, and gear S, and is provided with a hand-wheel, T. Gear S is bored out large enough to receive the small end of the thimble-piece 15, which is first passed through a hole in the bearing-piece 16, when gear S is slipped on to its end on the other side, thereby forming a shoulder on each side of the bearing-piece 16, the gear and thimble-piece being held together by the set-screw 17, which passes through them both, as fully shown in fig. 5. The bearing-piece 16 is fastened to frame A. Gear S may be made with a hub of sufficient size to have a groove turned in it large enough to use a common divided box or bearing to support the gear and its shaft Q. A shaft may be arranged at the side of the machine with a gear on it to mesh into gear S, the shaft running back to the rear of the machine, so that shafts Q and P can be operated to adjust the matcher-head frame D by the operator while standing at the rear of the machine.

I have shown only so much main frame and other parts of a planing and matching machine as was necessary to illustrate my invention. Frame A may extend to any desired length, and horizontal planing cutters may be arranged both behind and before the matcher-heads E E in the usual manner. It will be observed that when the swinging bed-piece C is drawn up and the nuts screwed down upon the top of the ears 10 10, the upper ends of the spindles F F are held firmly in place, while the horns J J being turned up firm against the rear ends h h of the arms H H, and the pawl m dropped into place in the ratchet-wheel N, all vibration of the lower ends of said spindles is prevented. The horns J J can be adjusted upon the hubs K K by means of set-screws 18.

The operation is as follows: When it is desired to use the machine for planing without matching, the operator turns up the nuts 9 9, and turns the bolts 8 8 forward, as shown in (blue lines) fig. 2. He then turns out set-screw 17 and pulls shaft Q out, as shown in (red lines) fig. 1, thereby disconnecting shafts Q and P. He next raises pawl m, and by means of the hand-wheel M' turns shaft M and its cam-arms L L and horns J J back, and by which operation the arms H H are drawn back, together with frames D D' and spindles F F, whereby the matcher-head and bed-piece C are depressed and swung down and back, as fully shown in red lines in fig. 2 of the drawings.

It will therefore be seen that by my invention the matcher-heads can be turned down very quickly out of the way and below the surface of the table B, and that, too, without disturbing the relative positions of the matcher-heads and their frames and spindles. When the matching mechanism is to be used again, shaft M is turned forward, forcing the parts back into the position shown in (dark lines) fig. 2, when the bolts 8 8 are turned up and nuts 9 9 screwed down, as before explained, thus holding the matching mechanism in place; pawl m dropping into position to hold the ratchet-wheel N and shaft M, and the parts connected therewith. Shaft Q is now pushed in so as to connect with shaft P, and set-screw 17 turned down, and the parts are again in proper position for matching. By the use of oblong slots g g in the arms H H, the bolts O O can be very accurately adjusted, so as to enable the friction-rolls 1 1 to play with ease in the slots y y in the arms L L.

Those skilled in the art to which my invention belongs will readily appreciate the advantages to be derived from my improvements.

Having described my improved matching machine, what I claim therein as new and of my invention, and desire to secure by Letters Patent, is—

1. Supporting the matcher-spindles and heads in a swinging frame constructed and operated substantially in the manner and for the purposes stated.
2. I claim, in a machine such as described, the combination of the swinging matcher-head bed or frame with the arms H, cam-arms L, and shaft M, substantially as herein shown and specified.
3. The combination of the arms H and connecting bolts o with the slotted cam-arms L, in the manner and for the purposes described.
4. The combination with the arms H H of the horns J J and the shaft M, substantially as and for the purposes set forth.
5. The combination with the rear ends of arms H H of the projections I I, and oblong holes or slots g g, for the purposes stated.

FRANK J. PLUMMER.
